(57) **CLAIM**

The ornamental design for a set of three seating modules, as shown and described.

DESCRIPTION

FIG. 1 is a reduced, top, front, right perspective view of the set of three seating modules of the claimed design;

FIG. 2 is a front elevation view of the shortest seating module of the set of three seating modules shown in FIG. 1;

FIG. 3 is a rear elevation view of the shortest seating module of the set of three seating modules shown in FIG. 1;

FIG. 4 is a right side elevation view of the shortest seating module of the set of three seating modules shown in FIG. 1;

FIG. 5 is a left side elevation view of the shortest seating module of the set of three seating modules shown in FIG. 1;

FIG. 6 is a top plan view of the shortest seating module of the set of three seating modules shown in FIG. 1;

FIG. 7 is a bottom plan view of the shortest seating module of the set of three seating modules shown in FIG. 1;

FIG. 8 is a top, front, right perspective view of the shortest seating module of the set of three seating modules shown in FIG. 1;

FIG. 9 is a rear elevation view of the intermediate seating module of the set of three seating modules shown in FIG. 1;

FIG. 10 is a front elevation view of the intermediate seating module of the set of three seating modules shown in FIG. 1;

FIG. 11 is a right side elevation view of the intermediate seating module of the set of three seating modules shown in FIG. 1;

FIG. 12 is a left side elevation view of the intermediate seating module of the set of three seating modules shown in FIG. 1; FIG. 13 is a front, left perspective view of the intermediate seating module of the set of three seating modules shown in FIG. 1;

FIG. 14 is a top plan view of the intermediate seating module of the set of three seating modules shown in FIG. 1;

FIG. 15 is a bottom plan view of the intermediate seating module of the set of three seating modules shown in FIG. 1; FIG. 16 is a top, front, right perspective view of the intermediate seating module of the set of three seating modules shown in FIG. 1;

FIG. 17 is a front elevation view of the tallest seating module of the set of three seating modules shown in FIG. 1;

FIG. 18 is a rear elevation view of the tallest seating module of the set of three seating modules shown in FIG. 1;

FIG. 19 is a right side elevation view of the tallest seating module of the set of three seating modules shown in FIG. 1;

FIG. 20 is a left side elevation view of the tallest seating module of the set of three seating modules shown in FIG. 1;

FIG. 21 is a front, left perspective view of the tallest seating module of the set of three seating modules shown in FIG. 1; FIG. 22 is a top plan view of the tallest seating module of the set of three seating modules shown in FIG. 1;

FIG. 23 is a bottom plan view of the tallest seating module of the set of three seating modules shown in FIG. 1; and,

FIG. 24 is a top, front, right perspective view of the tallest seating module of the set of three seating modules shown in FIG. 1.
